CLAIM

The ornamental design for an infant wrap device, as shown and described.

DESCRIPTION

FIG. 1 shows a front, perspective view of an infant wrap device, showing my new design;

FIG. 2 shows a front, elevational view of the infant wrap device shown in FIG. 1;

FIG. 3 shows a rear, elevational view of the infant wrap device shown in FIG. 1;

FIG. 4 shows a left side view of the infant wrap device shown in FIG. 1;

FIG. 5 shows a right side view of the infant wrap device shown in FIG. 1;

FIG. 6 shows a top, plan view of the infant wrap device shown in FIG. 1; and

FIG. 7 shows a bottom, plan view of the infant wrap device shown in FIG. 1.

FIG. 8 shows a front perspective exploded view of the infant wrap;

FIG. 9 shows the infant wrap device mounted on an infant;

FIG. 10 shows a rear exploded elevational view of the infant wrap device; and,

FIG. 11 shows a left side exploded view of the infant wrap device.

The broken lines shown illustrate portions of the infant wrap device that form no part of the claimed design.

The infant wrap device is shown with a symbolic break in its length. The appearance of any portion of the article between the break lines forms no part of the claimed design.

1 Claim, 9 Drawing Sheets
